Patented July 14, 1925.

Des. 67,789

UNITED STATES PATENT OFFICE.

ROBERT CHALIFOUX, OF MONTREAL, QUEBEC, CANADA.

DESIGN FOR A DOLL LABEL.

Application filed March 28, 1925. Serial No. 12,951. Term of patent 3½ years.

To all whom it may concern:

Be it known that I, ROBERT CHALIFOUX, subject of the King of Great Britain, residing at Montreal, Province of Quebec, Canada, have invented a new, original, and ornamental Design in a Doll Label, of which the following is a specification, reference being had to the accompanying drawing, forming part thereof.

The figure is an elevation of the label showing my new design.

I claim:

The ornamental design for a doll label, as shown.

ROBERT CHALIFOUX.
